CANDLE CUP

Preston J. Frazier, Jr., Houston, Tex., assignor to Faroy, Inc., Houston, Tex.

Filed June 24, 1966, Ser. No. 2,802

Term of patent 14 years

(Cl. D48—2)

FIG. 1 is a perspective view of a candle cup showing my new design;

FIG. 2 is an elevational view; and

FIG. 3 is a vertical sectional view.

I claim:

The ornamental design for a candle cup, substantially as shown.
